United States Patent Office

Des. 188,319
Patented July 5, 1960

188,319

CHAISE FRAME

Morton I. Thomas, R.D. 2, Box 182H, Monroe, N.Y.

Filed Dec. 18, 1958, Ser. No. 53,817

Term of patent 14 years

(Cl. D15—11)

Fig. 1 is a perspective view of a chaise frame embodying my design; and

Fig. 2 is a side elevation of the same.

The dominant features of my design are shown by means of full lines in the drawing.

I claim:

The ornamental design for a chaise frame, substantially as shown and described.
